UNITED STATES PATENT OFFICE.

FRED E. BAILEY, DECEASED, LATE OF MANCHESTER, NEW HAMPSHIRE, BY LAURA A. BAILEY, ADMINISTRATRIX, OF MANCHESTER, NEW HAMPSHIRE, ASSIGNOR, BY MESNE ASSIGNMENTS, TO UNITED SHOE MACHINERY CORPORATION, OF PATERSON, NEW JERSEY, A CORPORATION OF NEW JERSEY.

WELT-ATTACHING MACHINE.

1,282,726.

Specification of Letters Patent. Patented Oct. 29, 1918.

Application filed February 16, 1917. Serial No. 149,118.

To all whom it may concern:

Be it known that FRED E. BAILEY, late of Manchester, in the county of Hillsborough and State of New Hampshire, deceased, invented certain Improvements in Welt-Attaching Machines, of which the following description, in connection with the accompanying drawings, is a specification, like reference characters on the drawings indicating like parts in the several figures.

This invention relates particularly to welt attaching machines and is herein illustrated as embodied in a machine especially designed for attaching a strip of welting to a shoe sole.

In the manufacture of McKay sewed shoes it is frequently desired to attach a strip of welting to the marginal portion of the upper surface of the outersole of the shoe. This welt, commonly termed a "mock welt", does not perform the usual function of a welt but is applied chiefly or solely in order that the finished shoe may have the appearance of a welt shoe so far as possible. The strip of welting has commonly been attached to the sole by means of metallic fastenings inserted near the inner edge of the welting where they will be covered when the sole is attached to the upper. It has been found desirable to supplement the metallic fastenings by the application of cement to the lower surface of the welt in order to effect a closer union of the welt and sole and thereby impart a more finished appearance to the shoe. Heretofore, the application of cement has been a hand operation and consequently comparatively slow and expensive and lacking in uniformity and neatness.

The general object of the present invention is to provide an improved machine which, without sacrifice of other utility, shall be especially adapted for so performing the above-mentioned welt attaching operation as to eliminate the necessity of applying the cement in a separate manual operation.

In accordance with this object of the invention, the illustrated machine is organized to nail the welting progressively to the sole and at the same time to apply cement progressively to one surface of the welting as

the welting is led step by step to the fastening inserting point, the metallic fastenings pressing the successive portions of the welt against the sole to cement the welt to the sole and thereby supplement the holding power of the fastenings. By thus simultaneously tacking and cementing the welt progressively to the sole, not only is the welting securely attached, but all parts of the welting are caused to adhere uniformly to the sole, eliminating cracks between the welting and the sole.

It is important to the satisfactory attachment of welting that the welting be soft and pliable. To this end, it is usual to nail the welting while it is in temper, that is, in a somewhat moist condition. It has been found that the welting can be rendered substantially more pliable and its handling and proper attachment thereby materially facilitated if heat is applied to the moistened welting just prior to the welt attaching. Furthermore, even though the cement reservoir is heated so that the welting is coated with the cement while the cement is in a heated condition, the cement coating on the welting is very liable to dry before the attachment of the welting to an extent to impair the holding power of the cement or prevent effecting proper adhesion between the surfaces to be united. Also, the welting is liable to stick in the welt guiding parts as the cement coated welting is led to the nailing point. This tendency is aggravated if, as is usual in operations of the character above described, quick drying cement is employed, and the difficulty is particularly pronounced whenever the operation of the machine is suspended even temporarily.

To obviate these difficulties, the illustrated machine is organized not only to apply heat to the cement in the cement receptacle or reservoir but also to apply heat to the cement coated welting near the nailing point, thus rendering the welting substantially more pliable and also insuring that the efficiency of the cement will not be impaired and that the coated welting will not stick even during the periods of inactivity of the machine.

In addition to the said features of the invention, the illustrated machine also in-

cludes the provision of novel means for accurately and quickly severing the attached welting from the source of supply.

While the invention is herein described with particular reference to its utility in performing the particular operation above mentioned, it is recognized that various features of the invention may have other uses. It is also to be understood that the term "nailing" herein sometimes employed for convenience is not intended to be restrictive to any particular kind of metallic fastening. Other features of the invention will be brought out in the following specification 10 with its appended claims. A preferred form 15 of the machine organization is shown in the accompanying drawings in which,—

Figure 1 is a front elevation of the machine;

Fig. 2 is a top view of the welt holding racks and the cementing mechanism;

Figs. 3 and 4 are top and side views, respectively, of the welt severing device;

Fig. 5 is a section through the welt guide; 25 and

Fig. 6 is an end view of the welt guide.

As shown, the fastening inserting mechanism of the machine may conveniently be of the type disclosed in United States Letters Patent No. 611,405, granted on an application of Louis A. Casgrain, to which Letters Patent reference may be had for a detailed description of certain parts of the machine not herein fully shown and described.

The illustrated machine includes a column 10 on which is supported a stand 12 carrying a work support 14. The driver 16 carried in a driver bar 18 is operatively related 40 to the work support and has associated with it a nail supplying mechanism, as indicated by the depending arm 20 supporting the strip carrier and by the cutter carrying lever 22.

Welting is supplied to the work support 14 of the machine from racks 24 mounted on a bracket 26 supported on a cement receptacle 42 and hence, indirectly, by the column 10. These racks comprise a series 50 of parallel plates 28 of the desired contour which are held in spaced relation by means of bolts 30 and 32, the latter being extended at each end and slidably supported in bearings 34 and 36 upon the bracket 26. A handle 38 may be provided upon one of these bolts in order that the racks may be readily adjusted. Preferably a spring-pressed plunger 40, shown in dotted lines in Fig. 1, is mounted in the bearing 36 and this plunger 55 co-operates with suitable notches in one of the bolts 32 in order to retain the racks in adjusted position. The bolts 30 are preferably provided with rollers over which the strip of welting is delivered.

A cementing device is located between the

racks 24 and the work support and comprises a cement receptacle 42 attached to a bracket 43 on the column 10. To maintain the cement in the receptacle uniformly in proper condition, this receptacle is preferably provided with a steam chamber 44 to which steam may be supplied by means of a pipe 46 and from which it may be exhausted by means of a pipe 48. Journaled in operative relation to the cement receptacle 42 75 is a cement wheel 50 which is driven by means of a worm and gear, shown at 52, said worm being in turn driven from a pulley 54 upon the main shaft of the machine by means of a belt 56 running over an idler 58 and a receiving pulley 60. The pulley 60 is connected to the worm 52 by means of a friction clutch normally spring-pressed into engagement but adapted to be manually released by the handle 64. On the cement receptacle and adapted to bear against the descending edge of the cement wheel 50 is a scraper 66. The strip of welting is guided into contact with the cement wheel 50 by means of a guiding roller 68 mounted on a 80 stud 70 on the bracket 26.

Between the work support and the cementing device is a welt guide 72 which is intended to guide the welting to the nailing point for attachment to the sole. This welt guide is provided with a hollow chamber 73 to which steam is led from the supply pipe 46 and exhausted through a connection to the pipe 48. A stripper plate 74 is mounted at the entrance to the welt guide to remove any surplus cement which may have been applied to the strip of welting. By the provision of means for heating the welt guide, it is possible to apply heat locally to the strip of welting, to which cement has been applied, to render the welting more pliable and to soften the cement on the welt 100 just prior to the application of the welt to the sole, and also to insure that the strip of welting will not stick in the guide, even 110 during the periods when the machine is at rest.

After the strip of welting has been attached to the sole or other work by the combined use of cement and metallic fastenings, 115 it must be severed, preferably with a slanting cut, close to the point at which the last metallic fastening was inserted. To this end the machine includes a knife 76 adjustably mounted in the sliding holder 78 and held therein by a clamp screw 80. This knife may be conveniently actuated by means of a horizontally extending handle 82 which is pivoted to a bracket 84 supported on the frame of the machine and is normally held 120 in upward position away from the work by the action of a spring-pressed plunger 86. The downward movement of the knife is limited by the contact of a locked bolt 88 in the knife handle with a stop 90 so that the 130

welt will be exactly severed without injuring the sole. Movements of the knife are guided by a roller 92 on the blade holder 78 entering a slot 94 formed in the bracket 84. The upper end of the blade holder is pivoted at 96 to the handle 82.

In operation, rolls of welting of the desired character will be placed in the racks 24 and these racks adjusted by manipulation 10 of the handle 38 to bring the roll of welting of the desired character into alignment with the cement wheel 50. A strip of welting will then be led over the roller on one of the bolts 30 and under the guide roll 68 15 over the top of the cement wheel 50 to the welt guide 72. If the cement has been softened by previous heating, the cement wheel will be readily rotated by means of the belt 56 from the drive pulley 54 mounted on the 20 main shaft of the nailing machine. If, however, it is desired to operate the nailing machine while the cement is still cold, as when starting the machine in the morning, this may be readily accomplished by manipulation 25 of the clutch handle 64 to release the worm drive 52. The sole or other work to which the welting is to be attached may be placed upon the work support 14 and the strip of welting pulled through the welt 30 guide 72 into the desired relation with the sole. The nailing machine will then be operated in the customary manner to insert metallic fastenings to nail the strip of welting progressively to the sole and to effect 35 the cementing of these parts by repeatedly pressing them together as the nails are inserted. After the last fastening has been inserted, depression of the knife 76 by a quick blow on the handle 82 will sever the 40 strip of welting at the desired point and will thereby prevent waste of welting such as occurs where the welting is supplied in small pieces slightly longer than are necessary for the individual shoe.

45 Having thus described my invention, what I claim as new and desire to secure by Letters Patent of the United States is:

1. In a welt attaching machine, a work support, fastening supplying mechanism, a driver for inserting the fastenings, a rack for holding a strip of welting, means for guiding the welting as it is led from said rack to a point adjacent to the fastening inserting point, and means interposed between said rack and said guide for applying cement to said strip of welting comprising a cement roll contacting with the welting and dipping in a cement receptacle.

2. In a welt attaching machine, a work support, nail supplying mechanism, a driver for inserting the nails, a rack for holding a supply of welting, a cement receptacle interposed between said rack and the work support, a rotatable cement wheel dipping in said cement receptacle, means for guiding

the welting progressively into contact with said wheel to coat one surface of the welting with cement, and means for simultaneously operating said nailing mechanism and said cement wheel.

70

3. In a welt attaching machine, a work support, nail supplying mechanism, a driver for inserting nails supplied by said mechanism, a rack for holding a supply of welting, a welt guide adjacent to the work support, means interposed between said welt guide and said welt rack for applying cement to one surface of the welting, and means for heating the welt guide to prevent the welt from sticking thereto during periods of inactivity of the machine.

75

4. In a welt attaching machine, a work support, fastening inserting mechanism, mechanism for supplying fastenings to said inserting mechanism, a cement receptacle, a cement roll dipping in said receptacle, means for guiding a strip of welting to the cement roll, a welt guide between said receptacle and the fastening inserting mechanism and constructed with a hollow chamber, and means for supplying steam to the chamber of the welt guide.

85

5. In a welt attaching machine, a work support, nail supplying mechanism, a driver for inserting the nails, a welt guide adjacent to the work support and constructed with a hollow chamber, a cement receptacle, a steam chamber surrounding said receptacle, a cement roll dipping in said receptacle, means for guiding a strip of welting 90 to said cement roll, and means for supplying steam to the chambers of said cement receptacle and said welt guide.

95

6. In a welt attaching machine, fastening inserting mechanism, a welt guide adjacent to the fastening inserting mechanism, a rack for holding a supply of welting, means interposed between said welt guide and said welt rack for applying cement to one surface of the welting, and means for applying heat to the welting in the welt guide to soften the welting just prior to the operation of the fastening inserting mechanism on the welting.

105

7. In a welt attaching machine, a work support, nail supplying mechanism, a driver for inserting nails supplied by said mechanism, means including a guide for supplying a strip of welting to said work support in position to be nailed to the sole, and means arranged to move downwardly and inwardly toward the driver for severing the strip of welting close to its point of attachment.

115

8. In a welt attaching machine, a work support, nail supplying mechanism, a driver for inserting nails supplied by said mechanism, a welt guide adjacent to the nailing point on said work support, a cement applying roll, means for maintaining a strip of 125

130

welting in contact with said roll, means for operating the driver and nail supplying mechanism, and means for driving the cement roll including a manually controlled 5 clutch element interposed between said operating means and said roll.

9. In a welt attaching machine, means for applying cement progressively to the surface of a strip of welting, means for supplying fastenings, and mechanism for inserting fastenings step by step through the successive portions of the welting and into a shoe sole thereby substantially simultaneously pressing the cement coated surface of the 15 welting against the sole.

10. In a welt attaching machine, a work support, fastening supplying mechanism, a driver for inserting the fastenings, and means coöperating with said fastening inserting mechanism for continuously applying cement to a strip of welting as the welting is led to the fastening inserting point.

11. In a welt attaching machine, a work support, metallic fastening supplying mechanism, a driver for inserting the fastenings, a welt guide adjacent to said work support, and means for supplying an extended strip 20 of welting to said welt guide comprising a plurality of racks each adapted to hold a

roll of welting, said racks being adjustably mounted on said machine and adapted to be moved to bring the respective racks into alinement with said guide.

12. In a welt attaching machine, a work support, a metallic fastening supplying mechanism, a driver for inserting fastenings supplied by said mechanism, a cement applying mechanism comprising a cement roll, and means for supporting a plurality of rolls of welting comprising a plurality of racks 35 mounted in parallel relation and adapted to be adjusted relatively to said machine to bring one of said racks into alinement with said cement roll.

13. In a welt attaching machine, a work support, fastening supplying mechanism, a driver for inserting the fastenings, a rack for holding a strip of welting, means for guiding the welting as it is led from said rack to a point adjacent to the fastening inserting point, and means interposed between said rack and said guide for applying cement of said strip of welting.

In testimony whereof I have signed my name to this specification.

MRS. LAURA A. BAILEY,
Administratrix of Fred E. Bailey, deceased.

Copies of this patent may be obtained for five cents each, by addressing the "Commissioner of Patents,
Washington, D. C."

It is hereby certified that in Letters Patent No. 1,282,726, granted October 29, 1918, upon the application of Fred E. Bailey, of Manchester, New Hampshire, for an improvement in "Welt-Attaching Machines," an error appears in the printed specification requiring correction as follows: Page 4, line 53, claim 13, for the word "of," first occurrence, read *to*; and that the said Letters Patent should be read with this correction therein that the same may conform to the record of the case in the Patent Office.

Signed and sealed this 14th day of October, A. D., 1919.

[SEAL.]

M. H. COULSTON,

Acting Commissioner of Patents.

Cl. 12—67.
